UNITED STATES PATENT OFFICE.

JENÖ FEJÉS, OF BUDAPEST, HUNGARY.

CYLINDER BLOCK FOR INTERNAL-COMBUSTION ENGINES.

Application filed June 17, 1926. Serial No. 116,693.

This invention relates to an improved cylinder block for internal combustion engines of the pressed steel type, in contradistinction to cast cylinder blocks.

5 A cylinder block mainly consists of a cylinder body, cylinder head which is also adapted to receive the valves, guides for the valve stems, induction piping, cylinder bed plate and water jacket in the case of water cooled engines, and of all these parts so far as stresses are concerned, the bed plate is the most important component, as it has to withstand all the stresses, viz, those due to the explosion and combustion within the cylinder or cylinders as well as those set up externally.

In the case of cast cylinders the bed plate is cast in one piece therewith, whilst in the case of pressed steel cylinders the bed plate has to be made separately and the cylinders have to be attached thereto in a gas-tight manner and so that the alignment of the cylinders shall be maintained and that no distortion shall be produced. The usual mechanical means are not suitable for this purpose as they are not reliable, nor sufficiently durable, quite apart from their excessive cost, and welding has been found to be the only practical means of attachment provided the joint between the end of the cylinder and the bed-plate is made sufficiently strong so as to be reliable under all working conditions.

The main object of the present invention is to provide a welded cylinder block of the pressed steel type for single or multi-cylinder internal combustion engines, in which the alignment of the cylinders is maintained and distortion prevented in the various parts of the cylinder unit, both during the welding process when the pressed steel cylinder unit is manufactured and subsequently under working conditions.

This object is attained by the provision of the following means for securing the cylinder or cylinders to the common bed plate. An external shoulder is provided near the lower end of the cylinder whilst the recess in the bed plate intended to receive the cylinder is formed with a flange having an inward projection followed by a downward projection whereby an annular recess or groove is formed between the said downward projection and the remainder of the bed plate, the inner surface of the downward projection being tapered so that after

the cylinder has been inserted into the recess with the shoulder thereof resting on the top of the bed plate and the cylinder end has been pressed out against the said tapered surface, the cylinder is locked in position, the lower edges of the said downward projection and of the lower end of the cylinder being then autogenously welded together by an oxy-acetylene flame or electrically.

Referring to the accompanying drawings which illustrate the invention by way of example,

Figure 1 is a sectional elevation of a cylinder block composed of cylinder units connected to a common bed plate.

Figure 2 is a sectional elevation showing the connection between the cylinders and the common base plate shown on an enlarged scale, whilst

Figure 3 illustrates the form of the end of the cylinder before it is widened to be secured to the bed plate.

Two cylinder units are shown on the drawing, each unit comprising a cylinder *a*, a cylinder head *b* in which also the valves are accommodated, an induction pipe *c* provided with a continuation *d* leading to the inlet valve, an exhaust pipe *e* and guides *d'* and *e'* for the inlet and exhaust valve respectively. The various units are connected together to form a block, the various cylinders *a* being connected to a common bed plate *f*.

According to the present invention the connection between each one of the cylinders *a* and the bed plate *f* is effected as follows:

The bed plate *f* is formed with a recess *g* for each one of the cylinders and with an annular flange comprising a projection *h* extending internally into the recess, which projection is followed by a downward projection *i* the inner surface of which is tapered as shown at *i'*. An annular groove *j* is thus formed between the downward projection *i* and the remainder of the bed plate. An annular shoulder *a'* is formed near the lower end *a''* of the cylinder, the inner surface of the said lower end being tapered as shown at *a'''*. The cylinder is first placed in position with the lower end *a''* projecting into the recess *g* and with the shoulder *a'* resting on the inwardly projecting flange *h* (see Figure 3). The lower end *a''* of the cylinder is then pressed out by

means of a conical mandrel or other suitable means until its outer surface abuts against the tapered surface i^1 provided on the downward projection i (see Figure 2). Finally 5 the two lower edges i^2 and a^4 of the downward projection and lower end of the cylinder respectively are welded together automatically as indicated at k .

It will be seen that according to the present invention the cylinder is firmly locked 10 in position and that by providing the metal weld k at the lower edges of the downward projection i and lower end of the cylinder whilst leaving a groove between the welding 15 surface and the bulk of the bed plate, the heat of the welding is localized whereby distortion is avoided. The welding edges preferably lie within the recess g above the lower surface f^1 of the bed plate whereby 20 the welded edges are protected from injury and destruction, this arrangement also permitting the surface f^1 of the bed plate to be machined without damaging the weld k .

What I claim is:—

25 1. A cylinder block of pressed steel for internal combustion engines comprising in combination a cylinder, a cylinder head, induction piping, a bed plate, a recess in the bed plate for the reception of the cylinder 30 and means for securing the cylinder to the

bed plate, said means comprising an external shoulder near the lower end of the cylinder, a flange forming integral part with the bed plate and constituted by an inward projection and a downward projection 35 whereby an annular recess is formed between the latter projection and the remainder of the bed plate, the inner surface of the downward projection being tapered, whereby after the cylinder end has been inserted into the recess formed in the bed plate with the shoulder resting on the top of the bed plate and the cylinder end has been pressed out against the tapered surface the cylinder is locked in position, and an outer 40 metal weld along the edges of the downward projection and end of the cylinder, for the purposes set forth.

2. A cylinder block as claimed in claim 1 and in which the inner surface of the 45 lower end of the cylinder is tapered.

3. A cylinder block as claimed in claim 1 and in which the edge of the downward projection and the edge of the lower end of the cylinder lie above the lower surface of 50 the bed plate, for the purpose set forth.

In testimony whereof I have signed my name to this specification.

JENÖ FEJÉS.
